CAL F. HUNTER, OF LOS ANGELES, CALIFORNIA.

INTERNAL-COMBUSTION MOTOR.

1,309,312.

Specification of Letters Patent.

Patented July 8, 1919.

Application filed September 9, 1916. Serial No. 119,217.

To all whom it may concern:

Be it known that I, JOHN P. BARKER, a citizen of the United States, residing at Tropico, in the county of Los Angeles and 5 State of California, have invented new and useful Improvements in Internal-Combustion Motors, of which the following is a specification.

This invention relates to internal combustion motors and more particularly to internal combustion motors in a cylinder of which a charge is initially compressed prior to the transfer of said charge to another portion of the cylinder for combustion to produce a 10 working stroke of a piston with which the cylinder is provided. The invention has for its object to provide an improved motor of the general nature stated in which high thermal efficiency and mechanical simplicity are 15 combined and which will operate at relatively high speeds. The invention is particularly applicable to motors operating on the two-stroke cycle and in which the forward portion of the cylinder is used as an 20 initial compression space or part of an initial compression space to which the charge is admitted prior to compression and transfer of the same to the combustion chamber at the other end of the cylinder. In such 25 motors as ordinarily constructed high initial compression and rapid charge transfer cannot ordinarily be combined in a motor having an open ended piston without elaborate and sometimes complicated pumping or 30 charge displacement appurtenances.

In accordance with the present invention, an open-ended and consequently non-water cooled piston may be employed in reasonably large installments, as a charge is first in- 35 ducted into the forward end of a cylinder and into the interior of a hollow piston as such piston is moved toward its cylinder head, a charge displacement element being provided at the forward end of said cylinder and supported in the cylinder in such manner that the piston in its reciprocation will cover and uncover the same thereby producing a pumping action. As a piston moves 40 in a direction to cover the charge displacement element such charge of gaseous fuel mixture as was in the previous stroke inducted into the interior of the piston will

be driven therefrom and transferred, preferably to an initial compression space provided in the wall of the cylinder where the 55 charge will be in readiness to enter the combustion end of the cylinder upon completion of the working piston stroke, an inlet port being provided in the cylinder wall for the admission of such initially compressed 60 charge, an exhaust port having been previously uncovered by the piston to permit the escape of the products of combustion formed by the firing of the preceding charge. The cylinder wall at the forward portion of 65 the cylinder is preferably provided with an uncontrolled port establishing communication between the interior of the cylinder forwardly of the piston therein and the aforementioned initial compression space, 70 and said initial compression space may be connected directly with the intake pipe or duct of the motor, which intake pipe may lead from any suitable source of gaseous fuel supply. A check valve, not shown, may 75 be provided to seal off the intake pipe and the same may serve as a compression wall of the initial compression space as in the internal combustion motor disclosed and claimed by me in another application for 80 U. S. patent, executed August 19, 1916, Serial No. 117,268. The charge displacement element and other features herein disclosed are likewise disclosed in said other application. The charge displacement ele- 85 ment preferably fills the major portion of the initial compression space when the piston is at the limit of its travel on the out stroke, and provision may be made as by slotting the charge displacement element for 90 the reciprocation of a connecting rod or piston rod therethrough. The induction of successive charges of incoming gaseous fuel, or constituents thereof, into the piston greatly lowers the temperature of the same 95 and the heat derived from the piston walls by the fuel is so prevented from escaping through the water jacket or other cylinder cooling means and is converted into useful work instead of being dissipated, as internal 100 combustion motors are essentially "heat engines", and such portion of the total heat energy of the fuel as is dissipated through the cooling medium is usually totally lost;

furthermore, the piston being thus internally cooled, more effective lubrication may be maintained as between the cylinder wall and the piston.

5 A further object of the invention is to provide an internal combustion motor which will be relatively simple and inexpensive in construction and organization when its features of superiority, such as, extreme light 10 weight combined with high power, torque, and fuel economy are considered.

With the above and other objects in view, the invention consists in the novel and useful provision, formation, combination, association and inter-relation of parts, members and features, all as hereinafter described, shown in the drawings and finally pointed out in claim.

In the drawings:

20 Figure 1 is a central, vertical, sectional, longitudinal view of an internal combustion motor cylinder and piston showing a charge displacement element therein;

25 Fig. 2 is a transverse sectional view taken on the line x^2-x^2 , Fig. 1, and looking in the direction of the appended arrows; and

Fig. 3 is a view similar to Fig. 1 and at right angles thereto, the piston being shown at the limit of its travel toward the cylinder 30 head.

Corresponding parts in all the figures are designated by the same reference characters.

Referring with particularity to the drawings in the embodiment of the invention 35 therein shown A designates the cylinder of an internal combustion motor, B designates a piston therein, C designates a charge displacement element, D designates means for securing said charge displacement element 40 in position in the forward portion of the cylinder A, E designates a piston rod, and F designates piston rod packing.

The cylinder A preferably comprises a cylindrical body portion 4 closed at one end 45 by head 5 and secured to other motor features such as the crank case 6 at its other end whereby in effect two cylinder heads are provided. A pocket 4^a is provided at the forward portion of the cylinder A the 50 same being in communication with the interior thereof through an uncontrolled port 4^b provided in the cylinder wall near the crank case 6, and through an intake port or ports 4^c provided for communication of 55 the pocket with the cylinder combustion space, namely, the space between the piston head and the cylinder head 5. An exhaust port 4^d is, or exhaust ports are, provided in the cylinder wall opposite the intake port 60 or ports 4^c. A water jacket 7 may surround portions of the cylinder and the interior of said water jacket may communicate with interior portions of the cylinder head 5 as through suitable ducts 8. However, any 65 other preferred method of keeping the cyl-

inder temperature lowered may be employed, such as, for instance, air cooling.

Said piston B comprises a cylindrical portion 9 closed at its one end as at 10 to form a piston head, and open at its other end to 70 permit moving the same over the charge displacement element C. The piston head 10 is provided with a semi-circular deflector 11 adapted to guide incoming gaseous charges toward the cylinder head 5 when the intake 75 port or ports are uncovered by the piston thereby driving out the products of combustion from the previous charge through the exhaust port or ports in the cylinder wall which were uncovered by the piston just 80 prior to the uncovering of the inlet port or ports, as the exhaust ports are preferably slightly longer longitudinally of the cylinder than the inlet port or ports. Connection is made between the piston B and suitable 85 means for converting piston movement into rotary motion by means of the piston rod E which passes through the charge displacement element C and the wall 6 of the crank case, being sealed against leakage of initially 90 compressed charge by means of the packing F which may be disposed in a suitable space provided in the wall 6 of the crank case. The piston is preferably secured to the connecting rod E by means of a screw 12 which 95 passes through the piston head 10 and into a boss 13 provided at the end of the piston rod. A suitable space is provided in the charge displacement element for the reception of the boss 13 as at 14.

100 The charge displacement element C is shown as a hollow cylindrical body 15 closed at its ends as at 16 and 17 and provided with a longitudinally ranging slot 18 extending far enough into the body to accommodate 105 the connecting rod E, which is preferably formed to nearly fill the slot 18, the walls of the cylindrical body 15 being throughout imperforate so that a charge being compressed cannot enter the hollow interior of 110 the body. The charge displacement element is of such proportions that when the piston B is in the forward end of the cylinder, nearly all of the space provided interiorly 115 of the piston is filled by the charge displacement element, thus resulting in the occupation of the pocket 4^a of the initial compression space by the charge, the same having been transferred from the interior of the cylinder and piston to such pocket 4^a from 120 whence it may escape through the inlet port or ports to the combustion space behind the piston.

125 The means D for securing the charge displacement element in position for co-action with the piston in compressing action may comprise a plurality of screws or the like 130 threaded through the crank case wall 6 and into the charge displacement element to hold the same snugly against the wall 6 forming 130

the initial compression cylinder head. The charge displacement element is provided with suitable internal bosses 20 into which the screws 19 extend.

- 5 The operation, method of use and advantages of the invention will be readily understood from the foregoing description taken in connection with the accompanying drawings and the following statement:
- 10 Upon movement of the piston toward its cylinder head a charge of gaseous fuel is drawn into the forward portion of the cylinder and into the piston through the intake pipe leading to the cylinder and through 70
- 15 the initial compression space, such charge passing through the narrow annular interspace provided between the piston and the charge displacement element to fill the piston as it recedes from its position over the 75
- 20 charge displacement element the charge in the meantime being thoroughly mixed, agitated and ground, such grinding action tearing apart or comminuting any particles of liquid fuel which may be in suspension in 80
- 25 the air of the incoming charge and said charge of necessity coming in contact with the inner walls of the piston will be heated, the charge being further benefitted by such heating and the piston temperature being 85
- 30 correspondingly lowered. On the stroke of the piston away from its cylinder head the charge just inducted into the interior of the piston will be expelled therefrom, returning along the path provided by the 90
- 35 narrow annular interspace between the piston and the charge displacement element with consequent further mixing and beneficial warming, and upon completion of the piston on this, its out stroke, the major portion 95
- 40 of the charge will have been transferred to the pocket formed at the cylinder wall and externally thereof and be in readiness to enter the combustion space behind the piston when the intake port is uncovered by 100
- 45 the piston. It will be understood that this transferring of the charge actually begins slightly in advance of the completion of the piston stroke, the piston finally displacing slight remaining portions of the charge 105
- 50 from the cylinder after it has started to uncover the intake port. With the major portion of the interior piston space filled by the charge displacement element high compression may be obtained in the pocket, 110
- 55 the degree of such compression depending entirely upon the capacity of the pocket or initial compression space. The charge admission to the combustion space, as before stated, is slightly later in the cycle of operations than the opening of the exhaust port, due to piston travel, though such exhaust port remains open during the entire period of opening of the intake port, and due to this arrangement of ports, the pressure of 115
- 60 the expanded gases, due to combustion, is 120
- 65 first relieved through the exhaust port, in cases where the pressure is greater than atmospheric, as in case of a full throttle opening, and the incoming charge has only to displace remaining products of combustion which cannot be above atmospheric pressure. The deflection of the incoming charge toward the cylinder head at the deflector 11 and the manner in which said incoming charge displaces remaining products of combustion will be well understood by those skilled in the art to which this invention appertains. Upon the return of the piston toward its cylinder head the intake and exhaust ports will be closed and 125
- 70 the entrapped charge in the compression space or combustion space is compressed to the desired volume and pressure by the piston, which will be moved toward its cylinder head through the connecting rod and 130
- 75 its connection with the other features of the motor as will be readily understood. At the proper point of piston travel in its stroke toward the cylinder head or in some cases slightly after it has reached the limit 135
- 80 of its travel toward the cylinder head, ignition of the charge may take place through suitable ignition devices such as the electric spark plug, not shown, and the resultant combustion or explosion of the charge will 140
- 85 again drive the piston to its position over the charge displacement element, displacing the charge inducted into the forward portion of the cylinder during the work of compression of the charge just fired, and 145
- 90 such displaced charge will be in readiness in the pocket 4^a to replace the products of combustion behind the piston. During the 150
- 95 working stroke of the piston the rotary element of the motor, or other device to be 155
- 100 actuated by the piston, will be actuated through suitable connecting devices co-acting with the piston rod E.
- Having thus disclosed my invention, I claim and desire to secure by Letters Patent:
- 105
- 110
- 115
- 120
- 125
- 130
- 135
- 140
- 145
- 150
- 155
- In an internal combustion motor, a cylinder having an initial compression space in one end thereof and a final compression space in the other end thereof, and also having an intake port leading from said initial compression space to said final compression space, a hollow piston mounted in said cylinder and controlling said intake port, a closure for the end of the cylinder provided with the initial compression space, a substantially cylindrical hollow charge displacement element having closed ends and detachably secured at one of its ends to the closure for the cylinder, the sides of the displacement element being spaced from the walls of the cylinder to receive the sides of the piston and the displacement element being formed with a longitudinal slot extending through the same from end to end and open-

ing laterally through one side thereof, and a piston rod extending through the slot and cylinder closure and connected to the piston, said piston rod being adapted to be 5 inserted laterally into position through the slot from one side of the displacement element.

In testimony whereof, I have signed my name to this specification in the presence of two subscribing witnesses.

JOHN P. BARKER.
